FISHING LURE

Paul M. Hesse, Detroit, Mich.

Application July 20, 1954, Serial No. 31,508

Term of patent 14 years

(Cl. D31—4)

Figure 1 is a side view of a fishing lure, showing my new design;

Figure 2 is a top view thereof;

Figure 3 is a front view of the fishing lure;

Figure 4 is a rear view of the fishing lure; and

Figure 5 is a cross-sectional view taken on the line 5—5 of Figure 1.

The dominant feature of my design resides in the full line portion of the drawing.

I claim:

The ornamental design for a fishing lure, substantially as shown and described.
